(57) **CLAIM**

The ornamental design for a medical implant, as shown and described.

DESCRIPTION

FIG. 1 is a perspective view of a medical implant, showing a new design;

FIG. 2 is a top plans view thereof; and,

FIG. 3 is a bottom plan view thereof.

The broken lines showing a medical implant are included for the purpose of illustrating environment and form no part of the claimed design.

1 Claim, 3 Drawing Sheets

FIG. 1

FIG. 2

FIG. 3
